(57) **CLAIM**

The ornamental design for a hat, as shown and described.

DESCRIPTION

FIG. 1 is a right side elevational view of a hat showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a bottom plan view thereof;

FIG. 7 is a top, front, right perspective view thereof;

FIG. 8 is a bottom, rear, left perspective view thereof;

FIG. 9 is cross-sectional view taken along line 9-9 of FIG. 2;

FIG. 10 is cross-sectional view taken along line 10-10 of FIG. 2;

FIG. 11 is cross-sectional view taken along line 11-11 of FIG. 2; and,

FIG. 12 is cross-sectional view taken along line 12-12 of FIG. 2.

The broken line showing is for the purpose of illustrating environment structure and forms no part of the claimed design.
